Wiedersheim-Praibanez.

ATTORNEYS.

UNITED STATES PATENT OFFICE.

ROBERT C. SAYRE, OF PHILADELPHIA, PENNSYLVANIA.

MAIL BOX.

Application filed August 21, 1923. Serial No. 658,504.

To all whom it may concern:

Be it known that I, ROBERT C. SAYRE, a citizen of the United States, residing in the city and county of Philadelphia, State of Pennsylvania, have invented a new and useful Mail Box, of which the following is a specification.

My invention relates to mail boxes in general, and more particularly to mail boxes which comprise a plurality of compartments for receiving letters or packages, which compartments being separately marked or identified, serve to relieve a postman or other person collecting from them of the labor of such separate assortment as would devolve upon him if all of the letters addressed to different destinations were entered together in one compartment or box.

The object of my invention is the construction of a compartmental mail box the compartments of which are separately externally marked with the destination or character of their intended contents, and in which locking devices are provided for maintaining the compartments normally closed until opened by the postman or other authorized person.

A further object of my invention is the provision of means for illuminating the designations applied to indicate the intended destination of the contents of given receptacles.

A further object is a simple, efficient and inexpensive construction of the mail box as an entirety.

With the foregoing, and other, objects in view, my invention comprehends a mail box of the character hereinafter described and claimed.

For the purpose of illustrating my invention, I have shown in the accompanying drawings certain types and embodiments of it which are at present preferred by me because in practice they will be found to give satisfactory and reliable results.

It is to be understood, however, that the various instrumentalities in which my invention is shown as embodied can be variously arranged and that my invention is not therefore limited to the precise arrangements which are typified in the constructions shown in the drawings and herein-after described.

Figure 1 represents a front elevation of a mail box embodying my invention.

Figure 2 represents a sectional, side elevation on the line 2—2 of the box illustrated in Figure 1.

Figure 3 represents a sectional plan on the line 3—3 of Figure 2.

Figure 4 represents a sectional plan on the line 4—4 of Figure 2.

Figure 5 represents a perspective view of a modified form of my mail box.

Figure 6 represents a sectional, side elevation of the mail box illustrated in Figure 5.

Figure 7 represents a sectional plan on the line 3—3 of Figure 6.

Similar numerals of reference indicate corresponding parts.

Referring now to Figures 1, 2, 3 and 4, 1 designates the back of my mail box which extends across the two compartments 75 which the box is shown as containing and which are respectively designated 2 and 3. The lower rear portion of the back is curved forwardly and inwardly to form an inclined directing bottom 4 common to both compartments.

The front face or the outer wall 5 of each compartment is shown as curved outwardly and extended downwardly and inwardly preferably to meet the bottom edge 6 of the 85 inclined bottom 4 of the box.

Paralleling each outer wall 5 is an inner wall 7 common to both compartments.

Between the outer and the inner walls 5 and 7 is a channel 8, substantially corresponding in length with the lengths of the inner and outer walls, the purpose of which is to form a slideway or bearing within which travels a sliding door 9 of about half the length of the channel 8, and adapted 95 when moved upwardly or downwardly, conveniently by a button 10 attached to it by a shank 11 which passes through a narrow vertical slot 12 in the front face 5, to open or close a discharge opening formed by slots 13 and 14 extending transversely across the lower parts of the two walls of each compartment of the box, and which are each, when not made continuous, essentially of a corresponding length and a width equal to the width of a compartment, so that when the door 9 of a given compartment is down in the position illustrated in Figure 2, it closes the discharge opening made by the said two slots 13 and 14, and closes the bottom of 110 said compartment.

When the button is moved upwardly to

the top of the slot 12, the sliding door is lifted and the slots 13 and 14 uncovered to form an opening for the discharge of its contents from a compartment of the box.

5 Each of the compartments is similarly slotted and similarly provided with a sliding door, and, of course, the compartments,—of which, as explained, there may be more than two,—are separated by a dividing wall 15.

10 The top of each compartment is provided with a light chamber 16 in which is contained an electric or other light 17, which casts its light upon a name plate 18, preferably of translucent material, upon a face of which is painted, or otherwise applied, the intended destination or designation of the contents of the compartment.

15 Below the compartments and exteriorly to them are fixedly attached holding hooks 19 to which may be attached the hooks 20 of a mail bag 21, illustrated as made of two compartments, which, when applied, will receive the contents of a given compartment.

20 22 designates a lock, the latch 23 of which normally locks a door 9 in its normally closed or down position as illustrated in Figures 1 and 2, and so prevents the dropping out of the contents of a compartment 35 until the unlocking of the lock of such compartment by a person authorized to collect from it.

25 24 designates the drop door or closure of the mouth piece of a compartment, which is pivoted on the pivot 25, as illustrated in Figure 2, and which normally is in the position illustrated in said Figure 2 until it is forced down by the action of letters or packages introduced through it. This contrivance is of the character usual in mail boxes, and its construction and operation are generally understood.

30 Referring now to the modified construction illustrated in Figures 5, 6 and 7,—the 45 form of the compartments is quadrangular instead of the curved front form of the construction already described, and the drop of the letters through the drop door 24 carries them into a tiltable receiving box 26, hinged at 27 along the bottom edge of an 50 opening 28 in the front wall of the mail box.

35 In the position shown in Figure 5, the tiltable receiving box 26 which is shown as embodying two compartments to correspond to the two compartments of the mail box, see 55 Figure 7, is shown in its dropped or opened position so that the letters can easily be taken out of it, while in Figure 6 the receiving box is shown in its normal position as 60 closed within the mail box proper.

A lock 29, of any preferred character and adapted to be opened by the person authorized to collect the mail, is typically illus-

65 trated in Figure 6, in which figure is also illustrated a directing plate 30, corresponding to the inclined bottom 4 of the first construction, which helps to direct the letters dropped through the drop door 24 into the compartments of the tilting receiving box 26 within the mail box.

70 While I have now described preferred embodiments of my invention, it is, of course, to be understood that in various particulars these embodiments may be further modified without departing from the spirit 75 or scope of the invention or sacrificing any of its advantages.

Having thus described my invention, what I claim and desire to secure by Letters Patent is:

80 1. A device of the character stated, comprising a casing the front wall of which is provided with sets of grooved ways, said front wall being formed upon a curved line from a portion adjacent the casing top to its bottom, a partition for said casing to provide separate mail receptacles arranged side by side, a letter drop for each receptacle, indicia above each letter drop denoting city mail for one receptacle and out-of-city mail for the other receptacle, a bottom discharge opening for each receptacle and a pair of doors each having a handle, said doors conforming to the curve of said front wall and arranged side by side in the said ways for closing said discharge openings, the casing front wall being provided with spaced, vertical slots for the working therethrough of said door handles.

85 2. A device of the character stated, comprising a casing the front wall of which is provided with sets of grooved ways, said front wall being formed upon a curved line from a portion adjacent the casing top to its bottom, a rear wall for said casing which is perpendicular throughout the major portion of its extent and terminates in a bottom portion which converges with the front curved wall at its bottom, a partition for said casing to provide separate mail receptacles arranged side by side, a letter drop for each receptacle, indicia above each letter drop denoting city mail for one receptacle and out-of-city mail for the other receptacle, a bottom discharge opening for each receptacle and a pair of doors each having a handle, said doors conforming to the curve of said front wall and arranged side by side in the said ways for closing said discharge openings, the casing front wall being provided with spaced, vertical slots for the working therethrough of said door handles.
